CLAIM

We claim the ornamental design for a cap with tab, as shown and described.

DESCRIPTION

FIG. 1 is a perspective view of the cap with tab according to our new design;

FIG. 2 is a top view of the same;

FIG. 3 is a lower view of the same;

FIG. 4 is a left side view of the same;

FIG. 5 is a right side view of the same;

FIG. 6 is a front view of the same;

FIG. 7 is a rear view of the same;

FIG. 8 is a perspective view of the tab of the cap with tab;

FIG. 9 is a top view of the same;

FIG. 10 is a front view of the same;

FIG. 11 is a left side view of the same;

FIG. 12 is a right side view of the same;

FIG. 13 is a lower view of the same; and,

FIG. 14 is a top view of the same.

1 Claim, 8 Drawing Sheets
